ILLUMINATING-BODY FOR ILLUMINATING-PROJECTILES.

1,079,821.

Specification of Letters Patent.

Patented Nov. 25, 1913.

Application filed May 27, 1913. Serial No. 770,202.

To all whom it may concern:

Be it known that I, FRIEDRICH ZIEGENFUSS, residing at Essen-on-the-Ruhr, Germany, a subject of the Emperor of Germany, have invented a certain new and useful Improvement in Illuminating-Bodies for Illuminating-Projectiles, of which the following is a specification.

The present invention relates to illuminating bodies for projectiles, particularly to an illuminating body deposited in a projectile, which ignites during the flight and simultaneously is thrown out from the projectile body.

15 In the accompanying drawing is illustrated one embodiment of the present invention and Figure 1 shows a central longitudinal section of the illuminating body, and Fig. 2 a cross section of Fig. 1 along line 20 2—2.

The illuminating body has a cylindrical housing A, in which the illuminating material B is deposited. The latter does not constitute a single body but consists rather of 25 several sections or parts having sector-shaped cross section, see Fig. 2, each of which is inclosed in a casing b¹, which preferably is made of plate and open at both ends. The sections of the illuminating material are secured in the housing A by means 30 of a cover plate C, see Fig. 1, carried by a bolt D which is screwed into the bottom of the housing A. The spaces between the radial walls of the casings b¹, as well as between the casings and the inner wall of the 35 housing A and the bolt D are filled with an easily melting material such as for instance paraffin. At the upper end of each section of the illuminating material is embedded a 40 fulminant. These fulminants will cause the ignition of the illuminating material and are for this purpose exposed through the small holes c¹ in the cover plate C. The ignition of the fulminant b² takes place 45 through the time fuse of the projectile. The bolt D is formed into a swivel spindle d¹ for the eyelet E on the outside of the housing A, which eyelet is constructed to receive a parachute, not shown in the drawing.

50 The manufacture of the illuminating body is accomplished in the following manner: The illuminating material is first filled into each of the casings b¹ on a press. The individual sections of the illuminating material 55 are thereupon inserted into the housing A

which is provided with a bolt D and the whole dipped in a bath of paraffin. The above mentioned space between the partitions, will then be filled. The paraffin will also penetrate between the casings and the 60 illuminating mass. Finally the sections of the illuminating mass are secured in the housing A by means of the cover plate C. As the quantity of illuminating material compressed into each casing b¹ is small, no 65 dangerous action would occur from an explosion of the illuminating mass through compression. The division of the illuminating material possesses therefore the advantage that illuminating bodies of large dimensions, that is a dimension corresponding to the diameter of the projectile chamber, can be manufactured in the least dangerous manner. By means of the packing of 70 the space between the sections of the illuminating mass is moreover attained that the igniting gases of the fulminants b² can only reach the upper surface of the illuminating mass, and are therefore not able to ignite 75 from the sides or from underneath, which would cause the explosion of the illuminating mass or the ejection thereof from the housing A. The packing insures therefore a slow and regular burning of the illuminating mass.

By providing, for its ignition, an individual fulminant b² for each section of illuminating mass, and by having each section of the illuminating mass, in consequence of its sector shape, extending to the bottom of 80 the housing A, is furthermore attained that all of the sections of the illuminating mass are assured the greatest security for being ignited by these fulminants and of being entirely consumed. This security would not 85 exist if the illuminating mass consisted of rings or disks piled one above the other, as in that case the flame had to be transmitted from one ring or disk to another situated beneath it.

100 I claim:

1. An illuminating body for illuminating projectiles comprising a housing, a plurality of sections of illuminating mass, said sections acting independently from each other and being separated from each other and from the housing by means of an easily melting material.

105 2. An illuminating body for illuminating projectiles comprising a cylindrical housing 110

- closed at one end, and a plurality of sections of illuminating mass, each extending the whole length of the housing, a casing for each of said sections open at both ends, 5 means for securing said sections in the housing, and a filling material for the space between the individual sections and the housing, said filling material consisting of an easily melting matter.
- 10 3. An illuminating body for illuminating projectiles, comprising a cylindrical housing closed at one end, a plurality of sections of illuminating mass, each extending the whole length of the housing, a casing for 15 each of said sections, means for securing said sections in the housing and a filling material for the space between the individual sections and the housing, said filling material consisting of an easily melting 20 matter; a fulminant in each of said sections at the open end of said housing.
4. An illuminating body for illuminating projectiles comprising a cylindrical housing closed at one end, a plurality of sections 25 of illuminating mass, each extending the whole length of the housing, a casing for each of said sections, means for securing said sections in the housing and a filling material for the space between the individual 30 sections and the housing respectively said filling material consisting of an easily melting matter; and a fulminant in each of said sections at the open end of said housing; 35 said means comprising a bolt secured in the bottom of the housing and a cover-plate at the open end of the housing.
5. An illuminating body for illuminating projectiles comprising a cylindrical housing
- closed at one end, a plurality of sections of illuminating mass, each extending the whole 40 length of the housing, a casing for each of said sections, means for securing said sections in the housing and a filling material for the space between the individual sections and the housing respectively said filling 45 material consisting of an easily melting matter; and a fulminant in each of said sections at the open end of said housing; said means comprising a bolt secured in the bottom of the housing and a cover-plate at 50 the open end of the housing and a plurality of holes in said cover-plate situated opposite said fulminants.
6. An illuminating body for illuminating projectiles comprising a cylindrical housing 55 closed at one end, a plurality of sections of illuminating mass, each extending the whole length of the housing, a casing for each of said sections, means for securing said sections in the housing and a filling 60 material for the space between the individual sections and the housing, said filling material consisting of an easily melting matter; and a fulminant in each of said sections at the open end of said housing; 65 said means comprising a bolt secured in the bottom of the housing and a cover-plate at the open end of the housing; and a swivel at one end of said bolt outside of said housing.
- The foregoing specification signed at Bar-
men, Germany, this 15th day of May, 1913.
